UNITED STATES PATENT OFFICE.

ALBERT CARMAN, OF WINNIPEG, MANITOBA, CANADA, ASSIGNOR TO HIMSELF AND ARCHER MARTIN, OF SAME PLACE.

SAD-IRON.

SPECIFICATION forming part of Letters Patent No. 427,298, dated May 6, 1890.

Application filed May 28, 1889. Serial No. 312,415. (No model.)

To all whom it may concern:

Be it known that I, ALBERT CARMAN, of Winnipeg, in the Province of Manitoba and Dominion of Canada, have invented a new and useful Improvement in Sad-Irons, of which the following is a full, clear, and exact description.

The invention relates to improvements in sad-irons; and it consists in the particular construction and arrangement of parts, as hereinafter fully described, and pointed out in the claim.

Reference is to be had to the accompanying drawings, forming a part of this specification, in which similar letters of reference indicate corresponding parts in all the figures.

Figure 1 represents a side elevation of a sad-iron embodying my invention; Fig. 2, a partly broken and sectional plan view of the same with a top cover, with which the sad-iron is provided, removed; Fig. 3, a mainly sectional longitudinal elevation upon the line *w w* in Fig. 2; Figs. 4 and 5, transverse sections upon the lines *x x* and *y y*, respectively, in Fig. 3; Fig. 6, an inside face view of a certain side cover or lid detached, and Fig. 7 is a detail sectional view of the rear end of the body and cover.

A is the hollow body of the sad-iron, which may be cast in a single piece, and which has opposite vertical side walls *b b*, joined at the ends, and a transverse partition *c* at a suitable distance from the front end of the iron, to form, in connection with the sides *b b* and ends of the iron, a front or end chamber *B*, closed below, which portion constitutes the hollow pressing-block of the sad-iron, and to further form or leave in rear of said chamber *B* a space or chamber *C*, open both above and below, adapted to receive the hollow pressing-roller *D*.

The top of the hollow body *A* is provided with a removable cover *E*, on which are erected the stanchions *G G*, that carry the wooden or other handle *H*. This cover *E* is fitted to its place by sliding and entering it down within upper raised portions of the side walls *b b* and projecting its one or front end under an end cap *d* on the body and within a groove *e* in the latter, while the other end of said cover

sits down on the cross-piece *f* of the body and down within cleat-like projections *g g* thereon, when the cover may be secured in place by a spring-catch *h* on it, that may be provided with a suitable knob, engaging with a stud *i* on the cross-piece *f*.

The chamber *B* is designed to contain a loose heating solid metal core *I*, which may be readily entered down within said chamber or be removed therefrom, as required; by releasing the catch of the cover *E* and lifting off or removing said cover. The hollow pressing-roller *D* is also made to contain a removable heating metal core *J*.

Each sad-iron may have any number of additional cores *I J*, that in practice may be kept heated to replace the cores in the iron as they cool, and to provide for reheating the latter without occasioning serious delay in laundering goods by the iron.

When the heated cores are in their place in the implement, the necessary heat of course will be transmitted through that shell portion of the body of the iron and base-piece of the chamber *B* which constitutes the fixed pressing-block of the iron, and through the movable shell or hollow pressing-roller *D*, that projects slightly below the bottom of the body of the sad-iron, which latter may be manipulated over its work as ordinary sad-irons are.

To the side walls *b b* of the body *A*, which are suitably apertured and recessed for the purpose, are fitted opposite side-lids *K K*, covering the space occupied by the hollow pressing-roller. These lids are each made with a projecting circular inner rim or flange portion *k*, adapted to form bearings for and to receive freely over them the open ends of the hollow pressing-roller *D*, and by removing these lids said roller may be readily entered to its place through the open bottom of the body *A*, and may be as readily removed when necessary to clean or replace it. Ordinarily, however, it will only be necessary to remove one of said lids *K* for the purpose of inserting and removing the heating-core *J*, and this lid, that may be provided with a knob *l*, may be secured in position by sliding it to its place over a guide-like projection *m* on the bottom of the side of the main body passing through a re-

cess *n* in said lid *K*, so as to bring key-holes *o o*, with which said lid is provided, in line with rotatable catches or pins *s s*, projecting from the body *A* and having a lip or ear on 5 their outer end. By turning these catches or buttons so that their lips or ears will be in line with the key-holes *o o* the said side lid may be readily fitted to its place or removed, as required, and when in its place may be fastened therein by turning the catches *s s* so that their lips or ears come out of line with the key-holes. The cores *I J* virtually form a part, as it were, of the fixed presser-block and pressing-roller portions of the sad-iron, inasmuch 15 as, in addition to their heating function, they give the necessary weight thereto.

The stationary or fixed hollow heated press-
ing-block portion of the iron operates very ad-
vantageously to prepare the surface to be
20 ironed for the after smoothing and ironing ac-
tion of the heated pressing-roller, and the two

pressing portions combined act much more ef-
fectually than either one separately could do.

Having thus described my invention, what I
claim as new, and desire to secure by Letters 25
Patent, is—

In a hand sad-iron, the combination, with
the hollow body *A*, having an open-bottomed
chamber *C*, of lids or covers to said chamber
at the sides of the body, having inner flanges 30
or bearings *k*, and the hollow pressing-roller
D, fitting at its open ends loosely on or over
said bearings and arranged to project through
the bottom of the body, one of said covers be-
ing made readily removable and provided 35
with suitable fastenings for holding it closed,
substantially as herein set forth.

ALBERT CARMAN.
